(57) **CLAIM**

The ornamental design for a watch, as shown and described.

DESCRIPTION

FIG. 1 is a perspective view of a watch showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front view thereof, showing an alternate environment;

FIG. 9 is an enlarged view of a portion of FIG. 2; and,
FIG. 10 is an enlarged view of a portion of FIG. 8.

The uniform dashed lines illustrate structure or features which form no part of the claimed design.

The dot-dash broken lines in FIGS. 2 and 8 encircle portions of the claimed design that are shown enlarged in FIGS. 9 and 10, respectively.

The claimed design includes the hour, minute, and second hands on the front face of the watch, but the particular position of the hands forms no part of the claimed design.
